UNITED STATES PATENT OFFICE

HOLLIS L. BROADFOOT, OF FLORENCE, ALABAMA

COMMODE SEAT

Application filed November 29, 1929. Serial No. 410,553.

This invention relates to an improved combined commode seat and cover and one of the objects of the invention is to provide a device of this class which will be so constructed as to be devoid of any such means for holding the cover upon the seat, which means would be liable to become fouled and render the device unsanitary.

Another object of the invention is to provide means for retaining the cover upon the seat, which means will be devoid of any moving elements, but which will function automatically simply through rotation of the cover upon the seat.

Another object of the invention is to provide a commode seat especially adapted for children's use.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a vertical sectional view through the combined seat and cover embodying the invention, the same being mounted upon the top of a commode, and a combined handle and retaining means being shown in elevation.

Figure 2 is a top plan view of the device, the view illustrating in broken lines the contour of the opening which is provided in the seat.

Figure 3 is a vertical front to rear sectional view taken substantially on the line 3-3 of Figure 2 illustrating the cover and the parts associated therewith in locked or retained position in full lines and released or disengaged position in dotted lines.

Figure 4 is a plan view of one of the blanks from which the handle and retaining means are formed.

The device embodying the invention is capable of general application to commodes,

such a vessel being shown in the drawing, and indicated by the numeral 1, and includes a seat which is indicated by the numeral 2 and which in itself is substantially circular in form and has a downturned periphery 3 adapted to fit over and engage about the upturned portion of the commode as best shown in Figures 1 and 3 of the drawing. This seat may be made of any material, such for example, as enameled iron, porcelain or the like, and in accordance with the invention, it is formed with a symmetrically shaped opening 4 which in general contour is elliptical, the seat being molded, cast or otherwise formed so that the opening is surrounded by a downwardly and inwardly curving flange, indicated in general by the numeral 5 and, by reference to Figures 1, 2 and 3 and by comparison of Figures 1 and 3, it will be observed that the lateral portions of the flange 5, which portions are indicated generally, by the numeral 6, are extended downwardly a greater distance than the front and rear portions which are indicated by the numeral 7, and that the lower edge of this flange throughout these portions is extended on a gradually curved line. At this point it may be remarked that the contour of the seat and particularly the form of the opening therein, in itself constitutes a novel feature of the invention, and that the same might be employed without the use of a cover.

However the invention contemplates the use of a cover and the construction of the same will now be described. The cover comprises a flat circular plate 8 which may be of any desired marginal contour, although preferably circular, so as to adapt it to be disposed upon the upper side of the seat 2 in concentric relation thereto. The cover is of a diameter somewhat greater than the maximum diameter of the opening in the seat 2 so that when the cover is symmetrically arranged upon the top of the seat the opening will be completely closed or covered. The combined handle and retaining means for the cover is preferably formed from two blanks, one of which blanks is shown in Figure 4 of the drawing and is of sheet metal

and comprises a rectangular body 9 which is provided at each of its narrow margins with an integral extension, indicated by the numeral 10, which likewise is of rectangular form, these extensions being of the same length and being located midway between the ends of the respective edges of the body of the blank. In forming this blank, in the course of manufacture, the portions of the body of the blank, which might be divided by a line connecting the edges of the extensions 10 at either side thereof, and the outer end margins of the body, are struck up so as to provide portions 11 tending vertically from the intermediate portion 12 which constitute the under side of the handle and which is longitudinally curved as shown in Figure 1. The body of the blank is likewise formed to provide inwardly projecting flanges 13 at the upper edges of the side portions 11 and these flanges 13 have their free longitudinal edges either meeting or positioned close to each other.

The body portion of the member 9 comprises the handle portion and the extensions 10 thereof constitute means for assisting other means, to be presently described, in holding the cover upon the seat and likewise in holding the handle member and retaining means in place upon the cover, and as shown in Figure 1 of the drawing, the extensions 10 are inserted downwardly through slots 14 formed in the cover 8 at diametrically opposite sides of the center of said cover, and, immediately below the under side of the cover, these portions are curved outwardly and downwardly as indicated by the numeral 15, so that they will be restrained from being drawn upwardly through the openings 14 when the handle is grasped for lifting the cover. The lower ends of the portions 15 are provided with outstanding terminals 16 which constitute latch fingers engageable beneath the lower edge of the flange 5 and it will be observed by reference to Figure 1 that the portions 15 of the resilient handle member are normally sprung in opposite directions, so that their lower ends, constitute lugs 16, will engage with certainty beneath the lower edge of the flange 5. However, the outward spreading of the portions 15 is somewhat restricted so that while these portions, at their lug ends 16, engage with surety below the edge of the flange 5 when the same is rotated to the position shown in Figures 1, 2 and 3 of the drawings, when the handle member is grasped and the cover is rotated one quarter turn, the lugs 16 will be opposite the shallower portions of the flange 5, the same riding beneath the lower edge of the flange, and the cover may then be freely lifted from the seat.

As a means for holding and bracing the handle 17 with respect to the cover 8, a strip of sheet metal having a bend to form an arc-

uate portion 18 and outwardly extending or radial portions 19 is arranged at the time of manufacture at its intermediate portion in the tubular handle member formed by folding up the blank as shown in Figure 4, the portion 19 extending outwardly between the ends of this portion and bearing firmly at their under sides against the upper side of the cover.

It will be evident by referring to the drawings and particularly Figures 1 and 3 thereof, that the opening 4 of the seat of the invention is of considerably less diameter than the top of the commode upon which the seat is arranged, and therefore the seat of the invention is especially adapted for children's use.

What I claim is:—

1. In a combined commode seat and cover, a seat proper for disposal upon the open top of a commode and having an elliptical opening therein, a cover for the seat comprising a substantially flat body of greater diameter than the opening and disposable upon the seat and capable of rotation thereon, a handle upon the cover for rotation thereof upon the seat, and including resilient terminals extending downwardly from the cover in opposite directions and provided at their lower ends with lugs engageable beneath the seat at opposite sides of the opening therein upon rotation of the cover to one position.

2. In a combined commode seat and cover, a seat proper for disposal upon the open top of a commode and having an elliptical opening therein, a cover for the seat comprising a substantially flat body of greater diameter than the opening and disposable upon the seat and capable of rotation thereon, and retaining means upon the cover for holding it upon the seat, comprising resilient members extending downwardly from the cover in opposite directions and provided at their lower ends with lugs engageable beneath the seat at opposite sides of the opening therein, the lugs being spaced apart a distance less than the maximum diameter of the opening, the said seat having a downwardly extending flange surrounding said opening, the portions of the flange at and adjacent the minor diameter of the opening being of greater depth than the greater diameter of the opening, whereby when the cover is rotated, the said lugs will be caused to disengage from the lower edge of the flange both by reason of the upward curvature of the portions of the flange at the greater diameter of the opening, and likewise due to the fact that the lugs are spaced apart a distance less than the maximum diameter of said openings.

3. In a combined commode seat and cover, a seat proper for disposal upon the open top of a commode and having an elliptical opening therein, a cover for the seat comprising

a circular, substantially flat body disposable upon the seat and capable for rotation thereon, and a combined handle and retaining means upon the cover comprising a tubular handle member having resilient portions extending from its opposite ends through the said cover and provided at their lower ends with outstanding lugs for engagement beneath the flange of the seat, and a holding and bracing member having an arcuate intermediate portion housed within the tubular portion of the handle and terminal portions extending in opposite directions therefrom and bearing against the upper side of the seat.

4. In a combined commode seat and cover, a seat proper for the disposal upon the open top of a commode and having an elliptical opening therein, a cover for the seat comprising a substantially flat body of greater diameter than the opening and disposable upon the seat and capable of rotation thereon, and retaining means upon the cover for holding it upon the seat, comprising a handle member for rotating the cover and including resilient members extending downwardly from the cover in opposite directions and provided at their lower ends with lugs engageable beneath the seat at opposite sides of the opening therein, the said seat having a downwardly extending flange surrounding said opening, the portions of the flange at and adjacent the minor diameter of the opening being of greater depth than the portions at the greater diameter of the opening, whereby when the cover is rotated, the said lugs will be caused to disengage from the lower edge of the flange both by reason of the upward curvature of the portions of the flange at the greater diameter of the opening, and likewise due to the fact that the lugs are spaced apart a distance less than the maximum diameter of said opening, the portions of the flange at the shorter diameter of the opening being of greater depth than the portions of the flange at the longer diameter of the opening, and the said lower edge portions of the flange being continuously curved.

In testimony whereof I affix my signature.
HOLLIS L. BROADFOOT.
